(57) **CLAIM**

(**) Term: **14 Years**

The ornamental design for a vest having physiological monitoring system, as shown and described.

(21) Appl. No.: **29/129,931**

DESCRIPTION

(22) Filed: **Sep. 25, 2000**

FIG. 1 is a front isometric view of a vest having physiological monitoring system, showing our new design in closed condition;

(51) LOC (7) Cl. **24-04**

FIG. 2 is a front isometric view of a second embodiment of the vest having physiological monitoring system;

(52) U.S. Cl. **D24/186**

FIG. 3 is a front view of the second embodiment;

(58) Field of Search **D24/186; 600/386,**

FIG. 4 is a rear view of the first and second embodiment;

600/388, 389, 393, 436, 484; 128/874, 875; 2/102; D2/828, 829

FIG. 5 is a rear view of the first and second embodiment, in open condition; and,

(56) **References Cited**

FIG. 6 is an isometric view of the second embodiment in use condition, the broken line showing of the human body being for illustrative purposes only and forming no part of the claimed design.
